UNITED STATES PATENT OFFICE.

ALEXANDER McLAREN, OF CHICAGO, ILLINOIS.

DESIGN FOR AN ICE-CREAM CONE.

52,894.

Specification for Design.

Patented Jan. 14, 1919.

Application filed May 31, 1918. Serial No. 237,649. Term of patent 14 years.

To all whom it may concern:

Be it known that I, **ALEXANDER McLAREN**, a citizen of the United States, residing at Chicago, in the county of Cook and State of Illinois, have invented a new, original, and ornamental Design for Ice-Cream Cones, of which the following is a specification, reference being had to the accompanying drawing, forming a part thereof.

Copies of this patent may be obtained for five cents each, by addressing the "Commissioner of Patents, Washington, D. C."

The figure is a side elevation of an ice cream cone showing my new design.

I claim:

The ornamental design for an ice cream cone substantially as shown.

ALEXANDER McLAREN.
